UNITED STATES PATENT OFFICE.

JOHN H. CHRISTMAN AND JOHN WINTER, OF SYRACUSE, NEW YORK.

IMPROVEMENT IN PHOTOGRAPHIC REFLECTORS.

Specification forming part of Letters Patent No. 150,135, dated April 28, 1874; application filed February 16, 1874.

To all whom it may concern:

Be it known that we, JOHN H. CHRISTMAN and JOHN WINTER, both of Syracuse, New York, have invented a new and useful Apparatus which we denominate an Adjustable Combination Photograph-Reflector, of which the following is a specification:

In the reflectors and screens heretofore used for deflecting light in photograph-galleries, it has been found difficult to modify and tone properly the shades and shadows, so as to give the desired fullness and rotundity to the features, and clearness and transparency to the shadows, for the most perfect effect. With the ordinary flat screen the high lights on the cheek, &c., are too great, producing a certain flatness in effect, while the shades on the neck, behind the ear and around the eye, on the side of the nose, &c., are too deeply tinted, thus taking away the fullness and rotundity so desirable for artistic pictures, in which there should be clearness in the shades and tints impossible to attain by the ordinary reflectors, in which the whole body of the reflected light is thrown in an unbroken mass sidewise flatly upon the face, and whether the surface of the reflector is white or blue, there is no means to modify or change its character.

Our invention was devised to obviate the difficulties heretofore experienced, and to furnish a reflector capable of furnishing any degree of reflected light, and direct it accurately on any desired point for producing the best effect.

The construction is as follows, referring to the accompanying drawing, in which a perspective view of the apparatus is shown.

An oblong frame, A, composed of two uprights, a cap, and sill, which connect at right angles, is supported in a vertical position by means of two foot-pieces, b b, from brackets on the top of which rods e extend up parallel with the sides of the frame A to the cap, which extends over the sides sufficiently to allow the upper ends of the rods to run up through it, one of said rods extending up some distance above the cap, to form a support for a jointed arm that carries on its end a horizontal screen, d, composed of a metal frame covered with thin tissue-paper or like material, and jointed to the arm by means of a pin projecting down at

right angles to the frame, and inserted in a socket in the end of the arm at e. The arm is jointed at e', and is attached to the rod e above the cap by a ferrule or ring that can slide up and down on rod e, and turn around on it. This construction gives to the horizontal screen every freedom of movement required. The lower half of frame A is occupied with a frame, B, covered on one side with tin or lead foil, or other like material, and on the other with a blue covering. This second frame, B, is pivoted in the stationary frame A on horizontal trunnions at the center of its height, so that it can be turned to any angle. The upper half of the stationary frame has a frame, C, similarly hung to that just described, and within this frame C are two other smaller ones, D D, that just fill its area, a vertical line dividing them. These frames D are covered in the same way as B, and are pivoted to frame C by trunnions at the top and bottom, at their centers, being, by this construction, movable at right angles to their outer supporting-frame C, as clearly seen in the drawing, where each of the frames is turned a little to show their varied action. In addition to the reflectors B D D, there are two oblong ones, E E', made like them. A rod, f, passes through each of these reflectors horizontally at the center of their length, on the inner ends of which are broad ferrules, that fit onto the rods e, and can slide up and down on them, or turn around, so as to revolve the screens E into any desired position, their angles to the horizon being determined by their turning on the rods f. The rods are generally to be held at the desired height by their friction on rods e, but set-screws or springs may be employed therefor if found necessary.

We have found by experiment that the best effects are produced by the use of the metallic surfaces described, and much more satisfactorily than white ones; and by the compound action of the several reflectors directing the rays of light with the force and exactness desired upon any point, the most perfect tints and shading are produced, far exceeding anything heretofore attained, and with a facility and exactness before unknown. For example, when the front side screen E or E' is properly adjusted, it has the effect to

deepen the color of the eyes; if the front and back screens are so placed as to cause their reflected rays to cross each other at the proper point upon the surface to be illuminated, and one of the screens D be turned with its blue surface reflecting onto the same place, so as to commingle the blue rays with the others, the compound rays will counteract the defects of a tanned or sallow skin, and will conceal freckles and other defects of like character.

The endless effects that can be accomplished with this apparatus leaves nothing to be desired more in the hands of a competent artist. The top screen d serves to soften and modify the lights from above when necessary.

The photographer well knows that the lights must be modified and varied with each sitter for the best effects; that thin subjects, or those with prominent muscles or veins, &c., must be softened down so as not to have them too conspicuous, which has been heretofore a very difficult matter to accomplish, but which, with this apparatus, can readily be done.

The lower screen B is used principally to throw a reflection with the blue side upon a

light dress, or with the metallic side upon a dark dress.

We claim in the above as follows:

1. The combination of the double screens B, D D, and E E', substantially as and for the purposes set forth.

2. The combination and arrangement of the screens E E' with the upright frame A, side rods e, and socket arm or rod f, as herein specified, so that they can be elevated, depressed, or turned in any direction.

3. The combination of the reflectors D with frame A, as and for the purposes specified.

4. The combination of the reflectors B and D, as and for the purposes set forth.

5. The combination of the reflectors D and E, as and for the purposes described.

6. The top screen d, constructed, arranged, and combined with the upright frame A and screens therein, as herein specified.

JOHN H. CHRISTMAN.

JOHN WINTER.
